(57) **CLAIM**

The ornamental design for a golf tee, as shown and described.

DESCRIPTION

FIG. 1 is a perspective view of a golf tee, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is perspective view of the golf tee, illustrating a golf ball operably positioned on the golf tee; and,

FIG. 9 is a front side elevational view thereof.

The broken line showing of a golf ball is included for the purpose of illustrating environmental structure and forms no part of the claimed design.
